FIG.1.

UNITED STATES PATENT OFFICE

CECIL M. WINBIGLER, OF LOS ANGELES, CALIFORNIA

PLAYING IMPLEMENT

Original application filed February 9, 1924, Serial No. 691,809. Divided and this application filed November 13, 1926. Serial No. 148,212.

My invention relates to a game to be played on a combination of game boards laid out to represent a golf course.

An object of my invention is to provide a unique club holder and unique miniature clubs for use in playing.

Another object of my invention is to provide a golf game which may be readily packed within a small space and transported at the will of the player.

A further object of this invention is to devise a golf game in which the motions of the clubs are similar to the motions of the actual game of golf.

15 The actual game of golf is played on a golf course composed of a series of golf holes, which vary in length, character of hazards and natural condition of the ground. In my invention it has been my desire to provide 20 within a limited space, such as the top of a dining room table, a game, comprehensive enough to embody a nine hole golf course, at a sufficiently large scale, to make the game interesting, and yet so arranged as to be 25 played within the previously stated limits.

It would seem that this can only be accomplished by using practically the entire space for each hole to be played. It is evident then that certain changes must be made 30 to provide nine holes, varying in length and character, and still keep within these limits, as the game is being played. My invention therefore provides that one of the boards shall revolve during the progress of the game, 35 thereby securing different conditions for various holes and yet not losing anything in scale. To lay out such a course in series, it would require nearly the entire area of an ordinary house.

40 There are certain unusual features embodied in my invention which can better be described and understood by reference to the accompanying drawings illustrating the different parts of the invention and the method of playing the game.

The device which is the subject of this application is a finger attachment with means for securely holding the shaft of the playing instrument therein, the configuration of 45 the device being such as to permit contact of

the thumb and forefinger and, further, to maintain the first joint of the finger rigid, thus enabling the player to manually operate the club in a vertical plane.

Referring to the drawings:

Figure 1 is a view in perspective of the game boards set for the first and second holes, with protecting net in place;

Fig. 2 is a plan view of a piece of metal after having been struck out of a large piece and before being bent into a finger attachment;

Fig. 3 is a view in perspective of the finger attachment with club in place;

Fig. 4 is a view in perspective of the back of the finger attachment with club in place;

Fig. 5 is a view in perspective of the finger attachment with club in place and engaged on the finger of the player;

Fig. 6 are views in elevation of the different clubs used in playing the game.

Reference is made to applicant's co-pending application Serial No. 691,809, filed February 9, 1924, patented November 16, 1926, No. 1,609,911 of which this is a division, covering in more detail the game board set forth in Fig. 1.

Referring to Fig. 1, it will be noted that the main sections of the game board do not set flush on the base or table, but are elevated. Board E, carrying the putting greens, is supported on a central pivot and four rollers. The section D hinged to the board C, carries the driving tees T' and T². The board C is supported by a triangular piece of any suitable material c extending the full width of the board. The board C is likewise supported by means of a bow-shaped spring which is fastened at its middle to the bottom of the board C. An auxiliary strengthening member helps to support the spring at its middle. Auxiliary strengthening braces also help to strengthen the spring at the center of each bow, where the spring contacts with the support base F. The ends are slotted, and pass over and slide on holding pins fastened to the bottom of the board C. The section of the board indicated by D is hinged to the section C along the joints g and is supported by the triangular piece h which is not attached to

100

the board. The two boards C and E form a free joint at *i* and by pressing on the board C near this joint, the spring is compressed to lower the upper edge of the board C below the lower edge of the board E, thereby allowing the board E to revolve freely. In this way it is possible to bring the various holes into position as the game is played.

The two tees marked T' and T² form the 10 tees for all the holes. The boards as shown in Fig. 1 are set for the first and second holes, H¹ and H². This set up also provides for the eighth and ninth holes, H⁸ and H⁹, as indicated along the joint *i*. By pressing on board 15 C, as will be later more fully described, it is possible to revolve board E into position so that the third and fourth holes, or H³ and H⁴, come into alignment with T' and T², then by releasing board C, the game is set for the 20 third and fourth holes. By again revolving board E so that the fifth hole or, H⁵, is in alignment with T², the boards are set for the fifth hole. By again revolving the boards to bring the sixth and seventh holes, or H⁶ and 25 H⁷, into alignment with T' and T², we have the boards arranged for the sixth and seventh holes. By again revolving board E, the original position, shown in Fig. 1, is secured, thus bringing H⁸ and H⁹, or the eighth and ninth 30 holes into position.

The greens G¹ and G² serve as the greens for all holes, the difference in the holes being provided for by the length of the fairways and position of the hazards as the board E is 35 revolved. It may be found advisable to provide freely movable hazards, such as bunkers to change the character of the holes as found desirable.

Referring now to Fig. 1, a moulding *j* is 40 provided under board E on the base F, to prevent the balls from rolling under the board during the progress of the game.

It will be noted that the four leaves of the base, indicated by *o* have hinged joints at *p*, 45 making it possible to fold them up into a box like receptacle. Three of the leaves are provided with small metal sockets at *k* into which the uprights, see Fig. 1, indicated by *l* are inserted. These uprights are bent at *m*, and 50 all the uprights considered together form a support for the net *n*, and provide a means for preventing the balls from rolling off the table as the game is being played.

Referring now to Fig. 3, I have shown a 55 finger attachment *x*, formed out of some suitable pliable sheet metal and overlapping on the back, see Fig. 4, so that it can be readily adjusted to fit different sized fingers. On the front of this finger attachment *x* is a 60 square socket *a'* into which the shafts of the various clubs *e'*, *f'*, and *g'* fit, (see Fig. 6). The socket *a'* forms a snug joint with the shafts of the clubs shown in Fig. 6. The finger attachment with club attached seems to 65 work best on the forefinger with the hand

in the position shown in Fig. 5. This finger attachment has an irregular top, see Fig. 2 showing metal before being bent into shape. The top is cut out at *b'* and *c'*; *c'* being cut lower than *b'*, in order that, when the attachment is adjusted to the finger, that portion of the forefinger indicated by *d'* Fig. 5 will be 70 uncovered. The metal is then bent into shape to fit around a finger (see Fig. 3).

Before the shot is made, the thumb is 75 pressed against the forefinger at *d'*, see Fig. 5, then when the forefinger is released the club head moves sharply forward, engaging the ball and sending it forward in flight, similar to the flight of a golf ball in an actual 80 game of golf. There are two purposes accomplished in giving an irregular contour to the top of this finger attachment. First, it provides a cut out place where the thumb can engage the finger, and, second, it provides means, namely, the upwardly projecting part *y*, whereby the lower joint of the forefinger can be held rigid. In this way it is necessary for the player to strike without using the joint nearest the end of the finger. By so 85 doing, it is possible to more nearly imitate the correct swing of an actual golf club in a real game of golf and the results are more satisfactory. A cloth or rubber lining *z* is provided for the inside of the finger attachment 90 to protect the finger of the player from the metal, and to provide a more secure hold thereto.

The clubs provided, see Fig. 6, *e'*, *f'* and *g'*, 100 resemble in the face of the club the actual golf clubs known as midiron, niblick and putter. All three clubs have their different uses in the game covered by my invention.

Referring again to Fig. 1, a suitable cloth covering is provided for the fairways, rough 105 and greens. A cloth similar to felt or canton flannel is best adapted both in color and texture for the fairways and greens. The rough is best secured by a more fibrous material, 110 brushed wool, or cloth with a similar texture serves admirably. A better result is secured if the boards are slightly padded before the final cover is put on. The tees, bunkers and greens are shown in contour. It is provided that these parts of the board shall be stamped out of some suitable metal, or moulded out of some suitable material. The whole board if practicable could be pressed out of paper pulp and then covered. The bunkers are 115 lined with cheap cloth lining, of sand or dirt color; rough is provided around the outer edge of these bunkers.

However, the covering is not necessary to the playing of the game and the boards could be used in a game such as described without 120 cloth covering. The same results could be secured by using a pressed cotton ball, or ball of other similar material, to prevent the ball behaving in too lively a fashion. Any ball 125 of any suitable material is satisfactory for 130

this game, which in size is in keeping with the scale of the boards. If cloth covered boards are used, the ball employed may be of any light material, such as cork, or a light hollow ball may be employed.

5 In playing the game, all players tee up on T' to start, see Fig. 1, as it becomes their turn and shoot for G¹, or the green of the first hole, the object being to hole out in hole w of this green, in the fewest number of strokes possible. The edges of the boards C and E as shown in Fig. 1, represent the boundaries of the course, and the player who is off the boards will be considered out of bounds, and 10 will be penalized one stroke. One out of bounds will be permitted to replace ball on the course at the point where it went out. The rules of golf apply in playing this game. The other holes follow in regular order, see 15 Fig. 1. I have shown this board as adapted for rotation in a clockwise direction to present the various holes, though it is to be understood that the direction may be varied. It would be a simple matter to arrange the 20 greens and hazards on board E of Fig. 1 in a different manner. However, this would not alter the method of playing the game, nor depart from the spirit of this invention.

The method of play is apparent from the 25 drawings and description, and considerable skill is required to successfully play the game with a low score.

The game played in competition becomes a source of much enjoyment and keen rivalry. 30 The net shown in Fig. 1 can be made from cheap green cheese cloth, which harmonizes admirably with the rest of the game.

While I have shown and described the preferred embodiment of my invention, I wish it 35 to be understood that I do not confine myself to the precise details of construction hereinbefore set forth, by way of illustration, as it is apparent that many changes and variations may be made therein, by those skilled in the 40 art, without departing from the spirit of the invention, or exceeding the scope of the appended claims.

I claim:

1. A playing implement for a golf game 45 employing miniature clubs, said implement comprising means adapted to fit on the index finger of the player and swing in a vertical plane, an angular socket carried by said means, and a golf club having a shaft adapted 50 to fit in said socket.

2. A playing implement for a golf game employing miniature clubs, said implement comprising a thin metal sheath adapted to fit on the index finger of the player and maintain 55 the first joint of said finger rigid, a golf club having a shaft, and means on said sheath for non-rotatably holding the shafts on the sheath.

3. A playing implement for a golf game 60 employing miniature clubs, said implement

comprising a thin metal sheath adapted to fit on the index finger of the player and maintain the first joint of said finger rigid, a socket carried by said metal sheath, and a golf club having a shaft adapted to fit in and be held 70 non-rotatably in said socket.

4. A playing implement for a golf game employing miniature clubs, said implement comprising a thin metal sheath having overlapping ends, capable of manual adjustment 75 to various size index fingers, and of maintaining the first joint of the finger rigid, a socket carried by said sheath, and a golf club having a shaft adapted to fit in and be held in said socket.

5. A playing implement for a golf game employing miniature clubs, said implement comprising a thin metal sheath having overlapping ends and capable of manual adjustment to various size fingers, said sheath being 80 so formed as to have cut out places at the sides, a socket carried by said sheath, and a golf club having a shaft adapted to fit in and be held by said socket.

6. A playing implement for a golf game 85 employing miniature clubs, said implement comprising a thin metal sheath having padded lining, overlapping ends, and capable of manual adjustment to various size fingers, said sheath being so formed as to have cut out 90 places at the sides and extensions in the front and rear extending to the second joint of the forefinger, a socket carried by said sheath and a golf club having a shaft adapted to fit in and be held by said socket.

7. A playing implement for a golf game 95 employing miniature clubs, said implement comprising a thin metal sheath lined with rubber, overlapping ends, and capable of manual adjustment to various size fingers, said sheath being so formed as to have cut out 100 places at the sides and extensions in the front and rear to the second joint of the forefinger, a socket closed at the upper end carried by said sheath, and a golf club having a shaft 105 adapted to fit in and be held by said socket.

8. In a device of the character described, a finger attachment for holding miniature golf playing implements, said attachment comprising means to cover the end of the finger and to maintain the first joint of the finger rigid so as to imitate the correct swing of an actual golf club.

In testimony whereof I affix my signature.

CECIL M. WINBIGLER.
